OR D 16,866

UNITED STATES PATENT OFFICE.

JAMES HUTCHISON, OF NEWARK, NEW JERSEY, ASSIGNOR TO A. FOLSOM & SON, OF BOSTON, MASSACHUSETTS.

DESIGN FOR OIL-CLOTH.

SPECIFICATION forming part of Design No. 16,866, dated August 24, 1886.

Application filed July 15, 1886. Serial No. 208,163. Term of patent 3½ years.

To all whom it may concern:

Be it known that I, JAMES HUTCHISON, of Newark, in the county of Essex, of the State of New Jersey, have invented and produced a new and original Design for Oil-Cloths or Painted Carpets, of which the following is a specification, reference being had to the accompanying photographic representation of such design.

In the said design, a central square, A, has extending from each side of it two other squares, B B, side by side, each having a side equal to half the length of that of the said central square. From each pair of the said squares a right-angled triangle, C, is extended, as shown, with its hypotenuse equal to one side of the central square. In each of the lesser squares, diagonally thereof, is a cross, D, having within it an opening, a, in the form of a cross, and containing a square, b, having arms c projecting from its sides, as shown; and there is in each of the right-angular spaces E, next the corners of the central square, a figure,

F, consisting, as represented, of half of that in one of the auxiliary squares. On the central square, A, and projecting beyond three of its sides into the next adjacent auxiliary squares, B, is a nosegay, H, as represented. Furthermore, each of the right-angled triangles C has within it an ornamentation, I, as represented.

In practice the essential features or parts of the design are to be in different colors, as may be desirable.

I claim—

The design shown and described, consisting of the central square, A, two auxiliary squares, B, the right-angled triangles C, and the intermediate triangles, E, arranged, as represented, and the nosegay and surrounding figures, as shown, disposed within the auxiliary squares B and triangles C and E, as set forth.

JAMES HUTCHISON.
